Edgar Montague Amphlett.

UNITED STATES PATENT OFFICE.

EDGAR MONTAGUE AMPHLETT, OF LONDON, ENGLAND.

GAME OF TABLE OR PARLOR CRICKET.

SPECIFICATION forming part of Letters Patent No. 728,187, dated May 19, 1903.

Application filed May 9, 1902. Serial No. 106,612. (No model.)

To all whom it may concern:

Be it known that I, EDGAR MONTAGUE AMPHLETT, a subject of the King of Great Britain and Ireland, residing at 13 Fairholme road, 5 West Kensington, London, in the county of Middlesex, England, have invented certain new and useful Improvements in Games of Table or Parlor Cricket; and I hereby declare that the following is a full, clear, and exact 10 description of the invention, such as will enable others skilled in the art to which it appertains to make and use the same, reference being had to the accompanying drawings, which form part of this specification.

15 The object of this invention is to provide means whereby the individual skill of the players can be exercised in a manner somewhat similar to that which obtains on the ordinary cricket-field. I attain this object by 20 means of mechanism illustrated in the accompanying drawings, in which—

Figure 1 shows in perspective apparatus constructed and arranged according to this invention. Fig. 2 is a detail view of the horizontal lever, hereinafter referred to; and Fig. 3 is a central section of the bridge or platform for mounting the wicket, hereinafter described in detail.

Similar letters relate to similar parts 30 throughout the several views.

Fig. 1 shows in perspective apparatus constructed and arranged according to this invention, in which *a* represents the movable base-board, with the figure of a batsman *b* attached thereto by means of the detachable angle-piece *c* and the thumb-screw *d*. The plunger rod or bolt *e* is held in an upright position by the angle-brackets *f*, each of the said angle-brackets being secured to the rear 35 of the batsman by means of the screws *f'*. The coiled spring *g* is supported by the collar-piece *h*, the said collar-piece being held in position by the cotter-pin *h'*. Hinged to the lower angle-bracket and suitably pivoted is 40 the bell-crank lever *i*, upon the upper or curved arm of which the plunger rod or bolt *e* presses and to the lower or straight arm of which the upper end of the bat *j* is secured by means of the screws *j'*. The lower end of the 45 bat *j* engages with the turned-up or pawl portion *k* of the horizontal hinged lever *l*, carried within the longitudinal slot *m* in the movable 50

base-board *a*. The horizontal hinged lever *l* is supported by the pin *n*, passing beneath it through the base-board, and is given free movement for the purpose of releasing the bat by the necessary pivots or fulcrums *n'*. The bat *j* is released by pressure in the direction indicated by the arrow upon the inclined portion or finger-rest *o* of the horizontal hinged lever *l*. The bat being thus disengaged from the turned-up or pawl portion *k* of the horizontal hinged lever *l*, the plunger rod or bolt *e*, aided by the coiled spring *g*, causes the bell-crank lever *i* to move in the direction indicated by the arrow and the bat to assume the position shown in the dotted lines *p*. To allow the bat unrestricted movement, so as to enable it to assume the position shown in the dotted lines *p*, and also to give free passage of the ball to the wicket if it is missed by the bat, the movable base-board *a* is cut away to a knife-edge at the portion *q*. The horizontal hinged lever *l* returns to its normal position by reason of the spring *r* when pressure is removed from the inclined portion or finger-rest *o*, and assuming a stroke to have been made the bat *j*, the lowermost end of which may be tipped with metal for its better engagement with the turned-up or pawl portion *k*, may now be returned to the normal "play" position. It will be noted that the movable base-board *a* has free movement beneath the bridge or platform *s*, carrying the stumps and bails or wicket, the ends of the 75 said bridge or platform being secured to the suitably-weighted feet *t* for the purpose of preventing the too easy movement thereof. The stumps are held in position on the bridge or platform *s* by their being placed in socket-holes *u*, Fig. 3. Immediately in front of the bridge or platform *s* is the guard-rail *v*, of any suitable material, to prevent the ball when missed by the bat from striking against the front of the bridge or platform *s* on either 80 side of the wicket and causing the bails to fall off by reason of the vibration thus set up. The bails should be placed somewhat firmly in deep grooves to diminish the chances of their being dislodged by vibration when the ball strikes the top of the bridge or platform *s* or by the reduced vibration when it strikes the guard-rail. That portion of the guard-rail *v* which is immediately in front of the 85

wicket is cut away to form the inclined plane *w* to enable the ball more easily to hit the wicket.

Fig. 2 shows details of the horizontal hinged lever *l* with the turned-up or pawl portion *k* and the inclined portion or finger-rest *o*.

Fig. 3 is a central section, to an enlarged scale, of the bridge or platform *s* and the guard-rail *v*, showing one of the socket-holes *u* and the inclined plane *w*.

When the apparatus is desired to be used, a strip of material A, preferably green baize, may be disposed longitudinally or diagonally upon a suitable table to form a miniature 15 "pitch" and the bridge or platform carrying the wicket may be arranged on and at right angles thereto and the movable base-board and attached batsman placed in position beneath the said bridge or platform, as shown 20 in Fig. 1 of the drawings. If now a player conveniently grasps the end marked B of the movable base-board *a* and places a finger on the inclined portion or finger-rest *o* of the horizontal hinged lever *l*, he will be able to 25 release the bat *j* at will and to have unrestricted movement of the movable base-board *a* within the limits of the feet *r* for the purpose of defending his wicket—that is to say, for example, the figure of a batsman may be 30 moved forward or to the right or to the left, according to the direction of the ball bowled, and at the desired moment the bat *j* may be released by pressure on the inclined portion or finger-rest *o*.

35 A celluloid ball of suitable dimensions may be used in the game.

The bowler may stand at a prescribed distance from the wicket and the players who field may be stationed around the table in 40 positions somewhat similar to those which obtain in the ordinary cricket-field. The batsman may be bowled or caught out, and runs may be scored by hitting the ball with the bat onto the floor or ground or against a 45 wall or other boundary agreed upon.

Having now described my invention, what I claim as new, and desire to secure by Letters Patent of the United States, is—

1. In a game of table or parlor cricket; the 50 combination of the figure of a batsman and the bat with the plunger rod or bolt; the bell-crank lever, having a suitably-curved upper arm and a straight lower arm; the angle-brackets, secured to the rear of the batsman

and holding the said plunger rod or bolt in 55 an upright position; and the coiled spring and collar-piece, embracing the plunger rod or bolt and providing the necessary propelling force; the said bell-crank lever being suitably pivoted to the lower angle-bracket, 60 the said plunger rod or bolt pressing upon its curved or upper arm, and the bat secured to its straight or lower arm.

2. In a game of table or parlor cricket, the combination of the figure of a batsman and 65 the mechanically-propelled bat with the movable base-board, having the longitudinal slot to receive the horizontal hinged lever, one end of the said movable base-board being shaped to be conveniently held by a player 70 and at the other end there being one portion provided with means for mounting the figure and another portion cut away to a knife-edge to give free passage to the bat; the horizontal hinged lever, pivoted in the longitudinal 75 slot of the said movable base-board, one end of the said horizontal hinged lever being turned up to form a catch or pawl for the purpose of retaining the bat, and the other end inclined to form a finger-rest; the spring for supporting the finger-rest and returning the said horizontal hinged lever to its original position when pressure is removed from the finger-rest; and the bridge for mounting the 80 stumps, or wicket, and guard-rail; the said 85 movable base-board being an apparatus whereby the said figure of a batsman may be moved in any direction necessary for the purpose of meeting the ball, and the said horizontal hinged lever being means whereby the said 90 mechanically-propelled bat may be held in the normal "play" position in opposition to the pressure exerted by the mechanism and whereby the said bat may be released at the will of the player operating the said movable 95 base-board so as to allow the said bat to fly forward and strike the ball simultaneously with the movement in any direction of the said movable base-board and the figure mounted thereon.

100 In testimony whereof I have signed my name to this specification in the presence of two subscribing witnesses.

EDGAR MONTAGUE AMPHLETT.
